UNITED STATES PATENT OFFICE.

HENRY CLINTON VAUGHN, OF JEFFERSON CITY, MISSOURI, ASSIGNOR OF
ONE-HALF TO LOUIS N. BARTON, OF JEFFERSON CITY, MISSOURI.

OIL-CUP.

No. 823,978.

Specification of Letters Patent.

Patented June 19, 1906.

Application filed May 19, 1905. Serial No. 261,228.

To all whom it may concern:

Be it known that I, HENRY CLINTON VAUGHN, a citizen of the United States, residing at Jefferson City, in the county of Cole and State of Missouri, have invented new and useful Improvements in Oil-Cups, of which the following is a specification.

The invention relates to an improvement in oil-cups, and particularly to a feed-cup arranged to automatically discharge its contents under the jarring influence of the operating machinery.

The main object of the present invention is the production of a cup having an adjustable discharge-opening which is normally closed when the machinery to which the cup is applied is at rest and which is automatically opened to permit discharge of the contents of the cup under the jarring influence incident to the operation of the machinery.

The invention in its preferred form will be described in the following specification, reference being had to the accompanying drawings, wherein—

Figure 1 is a view in elevation of my oil-cup. Fig. 2 is a vertical central section of the same. Fig. 3 is a transverse section of the feed-screw.

Referring to the drawings, 1 represents the base of the cup, comprising a cylindrical portion provided at its upper end with a concentric vertically-extending flange 2. The base portion is centrally formed with a longitudinally-arranged feed-channel 3, extending through the base portion and threaded at its lower end, as at 4, to receive the feed-screw 5. Immediately above the threaded portion 4 the channel is diametrically reduced to provide a valve-seat 6, with which a ball-valve 7, loosely seated in the channel, is arranged to coöperate.

Feed-screw 5 is provided with the usual conical end 8, arranged to coöperate with a conical seat 9, formed in the channel 3 below the seat 6. A longitudinal groove 10 is formed in the feed-screw to permit passage of the oil from the channel 3, as will be hereinafter explained.

A feed-tube 11 rises centrally from the base 1, being preferably formed integral therewith, a bore of the tube registering with the channel 3.

A body 12, preferably a glass cylinder, is seated at its lower end within the flange 2 of

the base, preferably seating upon a gasket 13 to prevent leakage. The body is concentric with the tube 11 and spaced therefrom to provide an oil-chamber 14, as is usual in devices of this character. The wall of the tube 11 is provided with a series of laterally-extending openings 15, terminally communicating with the interior of the bore and with the oil-chamber 14, whereby oil from said chamber is admitted to the tube. The upper end of the body 12 is engaged by a cap-plate 16 of suitable dimension having a depending flange 17 to receive the upper edge of the body and provided with a gasket 18, engaging said body edge to prevent leakage.

The upper end of the tube 11 projects centrally through the cap-plate and is engaged by a lock-nut 19 and by a headed screw 20, having threaded engagement with the interior of the tube, as clearly shown in Fig. 2.

The lower end of the base 1 is reduced and threaded at 21 for engagement with the machinery above the bearings and provided immediately thereabove with an angular portion 22 to receive a wrench or other tool for screwing or unscrewing the cup.

With the parts constructed and arranged as described and the cup in place above the bearings the vibrations of that portion of the machinery to which the cup is attached will cause more or less movement of the ball-valve 7, which is thereby continually moved to and from its seat 6 and insuring a constant supply of oil to the bearings, it being understood that the oil finds its way from the chamber 14 through the openings into the tube 11, past the valve 7, and lengthwise the feed-screw 5, through the channel 10 therein. Immediate the operation of the machinery ceasing the valve 7 returns to its seat 6 and instantly shuts off the supply of lubricant.

The cup described is automatic in operation, feeding oil to the bearing when only the shaft therein is in motion and cutting off said flow immediately the movement ceases, avoiding waste of the lubricant and insuring its use only when required.

It will be noted that the supply of lubricant fed to the bearing may be regulated by a longitudinal adjustment of the feed-screw 5 with relation to the seat 9, increasing or decreasing the channel at this point to increase or decrease the flow, as may be desired.

Having now described my invention, what

823,978

I claim as new, and desire to secure by Letters Patent, is—

A lubricator comprising a base, a cylindrical body supported on the base, a feed-tube within and in communication with said body, a feed-channel in the base and in communication with the bore of the feed-tube, an automatically-operable valve within said channel, the wall of said feed-channel being formed with a valve-seat below the valve,

and a feed-screw having threaded connection with the walls of the channel arranged to co-operate with said valve-seat, said feed-screw being formed with a longitudinal groove.

In testimony whereof I affix my signature 15 in presence of two witnesses.

HENRY CLINTON VAUGHN.
